COMPUTING DEVICE

William G. Stewart, Riverside, Ontario,
Canada

Application December 5, 1938, Serial No. 244,060

1 Claim. (Cl. 235—85)

This invention relates generally to computing devices and refers more particularly to improvements in devices of this character having provisions for determining certain informative data about different geographic locations.

It is one of the principal objects of this invention to provide a computing device composed of a relatively few simple parts capable of being inexpensively manufactured and readily operated to determine the desired information in regard to selected geographic locations.

Another feature of this invention consists in the provision of a computing device of the character set forth forming a folder or retainer capable of holding a map or other data. In accordance with the present invention, a strip of suitable material is folded intermediate its ends to provide opposite side portions and the latter are held in juxtaposition by a strap extending continuously around the side portions in a manner to retain the map or other data between the side portions.

Still another advantageous feature of this invention resides in the provision of a device of the type defined in the preceding paragraph wherein informative indicia is applied to the exposed surfaces of the side portions and wherein the strap acts as a finder for selectively indicating certain of said indicia.

A further object of the present invention resides in the provision of a computing device having a list of cities or towns on the exposed surfaces of the side portions with a column of mileage figures arranged opposite each city or town and having other cities or towns on the opposite sides of the strap corresponding in number to the number of mileage figures in each column opposite the cities on the side portions aforesaid of the computing device. The arrangement is such that by adjusting the strap or finder to a position in registration with any one of the cities listed on a side portion of the computing device, the mileage between the latter city and any one of the other cities on the finder may be quickly determined by merely reading the figure on the side wall portion of the device opposite the selected city on the finder.

In addition to the foregoing, the present invention contemplates a computing device rendering it possible to indicate information other than mileage between geographic centers. For example, the computing device may be conveniently employed to indicate telephone toll charges between certain cities or towns and/or the differ-

ences in time between different geographic sections.

The foregoing, as well as other objects, will be made more apparent as this description proceeds, especially when considered in connection with the accompanying drawings, wherein:

Figure 1 is a plan view of a strip of material having the desired informative indicia thereon;

Figure 2 is an elevation illustrating the strip in Figure 1 after the same has been folded intermediate its ends and also illustrating the finder in assembled relation;

Figure 3 is an elevation similar to Figure 2 and illustrating the other side of the device shown in Figure 2;

Figure 4 is a sectional view taken substantially on the line 4—4 of Figure 2;

Figure 5 is a plan view of a slightly modified form of construction;

Figure 6 is an elevational view of the strip shown in Figure 5 after the same has been folded intermediate its ends and illustrating the finder in assembled relation;

Figure 7 is an elevation of the other side of the construction shown in Figure 6;

Figure 8 is an elevation showing the free end portions of the adjacent side walls folded over;

Figure 9 is a cross sectional view taken substantially on the plane indicated by the line 9—9 of Figure 8.

Referring first to the embodiment of the invention illustrated in Figures 1 to 4, inclusive, it will be noted that I have shown in Figure 1 an elongated strip of folded material, such as heavy paper 10 having suitable indicia applied thereto on opposite sides of the median line, designated in Figure 1 by the reference character 11. Although the character of the indicia will, of course, vary in dependence upon the information it is desired to convey, nevertheless, for the purpose of illustration, I have selected indicia rendering it possible to indicate the mileage between different geographic locations. To this end, a column 12 is applied to the strip 10 on each side of the dividing line 11 to extend longitudinally of the strip and these columns are divided into a plurality of rectangular spaces 13 by lines 14 extending transversely of the strip. The transverse lines 14 are extended to points adjacent the opposite longitudinal edges of the strip and cooperate with each other to form transverse columns 15 opposite the spaces 13. In the present embodiment of the invention, the column 12 is arranged laterally between the longitudinal edges of the strips so that a column 15 extends

from each end of a space 13. The particular location of the column 12 laterally of the strip may, of course, be varied to suit conditions as will be more fully hereinafter understood.

5 Each space 13 contains indicia indicating different towns or cities and the columns 15 are divided into a plurality of squares 16 containing indicia indicating different mileage figures opposite each city or town in the spaces 13. The figures in each column 15 are, of course, predetermined to indicate the mileage between the city or town in the registering space 13 and other cities or towns applied to a feeler 17, which is slidably engaged with the strip 10 after the latter 15 is folded along the dividing line 11. It will, of course, be understood that the strip 10 is folded on the dividing line in such a manner that the sides of the adjacent wall portions carrying the indicia face outwardly.

20 The finder 17 is in the form of a strap extending continuously around the adjacent wall portions and serves the additional function of holding the wall portions in positions adjacent each other. It follows from the above that the opposite ends of the strap 17 extend across the adjacent longitudinal edges of the wall portions, with the result that a map or other loose data may be retained between the wall portions, if desired.

25 Applied to the outer surface of each side of the strap 17 is a column 18 extending longitudinally of the strap and divided into a plurality of spaces 19 by lines 20 extending transversely of the strap. The number of spaces 19 correspond to the number of spaces 16 in any one of the columns 15 and the spaces 19 are arranged to respectively register with the spaces 16. Upon reference to Figures 2 and 3, it will be noted that each space 19 on the strap 17 contains a city or town and, in the present instance, certain of the cities on the strap correspond to cities in the column 12 on the folder. In this connection, attention is directed to Figure 2, wherein it will be noted that the city "Cleveland, Ohio" appears in the column 12 on the folder and in the column 18 on the strap. Also, the strap is shown in Figure 2 as adjusted to a position in registration with "Cleveland, Ohio" in the column 12, and it will be observed that the space 16, in the column 15 extending from the latter city and registering with the city "Cleveland, Ohio" on the strap, is left blank. This procedure is followed wherever there is a duplication of cities or towns on the folder and strap.

30 The construction is such that the distance between any one town in the column 12 and any one of the cities on the strap 17 may be readily obtained by merely adjusting the strap to a position wherein the top edge 21 of the strap registers with the bottom line 14 of the space occupied by the selected city in the column 12 and reading the mileage figure in the column 15 opposite the selected city on the strap 17.

35 Assuming, for example, that it is desired to determine the distance between Cleveland, Ohio, and Washington, D. C., the operator merely adjusts the strap 17 to register the top edge of the strap with the bottom line 14 of the space in the column 12 occupied by the indicia "Cleveland, Ohio". After this setting of the strap is accomplished, the accurate mileage of 361 miles may be read in the column 15 opposite the space "Cleveland, Ohio" in the column 12 on the folder and registering with the space "Washington, D. C." on the strap. This setting of the computing de-

vice is illustrated in Figure 2 and it will be understood that the distances between any city in the column 12 on either side of the folded strip 10 and the cities on the strap 17 may be readily determined by following the same procedure.

40 It will be apparent from the foregoing that the computing device is extremely simple in construction and does not require the use of expensive materials. As a matter of fact, the manufacturing costs of the computing device are so low as to permit employing the same as an advertising feature and when designing the device for this use, sufficient space may be made available at the top edge 23 of both sides of the device for advertising matter.

45 Referring now to the embodiment of the invention illustrated in Figures 5 to 9, inclusive, it will be noted that the computing device is fashioned from a strip of material 25 having a length greater than the length of the strip 10 and adapted to be folded along the lines 26, 27 and 28. The strip 25 is shown in its folded position in Figure 8 of the drawings and it will be observed that folding the strip 25 along the lines previously described provides the device with opposed walls 25 29 and 29' having foldable flaps 30 and 30' at the upper ends thereof. The exposed surfaces of the opposed walls are provided with columns of indicia which, for the purpose of simplicity, is shown to impart the same information as the indicia on the opposed wall portions of the computing device previously described in connection with Figures 1 to 4, inclusive. The arrangement, however, is slightly different in that a column 31 of cities or towns is arranged on the side 35 wall 29 only of the folder and these cities or towns serve to identify the indicia on both side wall portions of the folder in a manner to be more fully set forth.

50 Upon reference to Figure 6, it will be noted that a column 32 extends transversely of the side wall 29 of the folder from each city or town in the column 31 and additional columns 33 extend transversely of the opposite wall 29', as clearly shown in Figure 7. The columns 33 are, in effect, continuations of the columns 32 and both columns are divided into a plurality of spaces 34 corresponding in number to the number of cities or towns applied to the opposite sides of the strap 35. Each space 34 continues a mileage figure 55 representing the distance between any one geographical location in the column 31 and any one of the locations on the strap.

55 As in the first described form of the invention, the strap 35 extends continuously around the side walls of the folder and is capable of sliding movement relative to the folder in the direction of the column 31. It may be pointed out that the cities or towns on the strap 35 correspond to certain of the cities or towns in the column 31 and, for this reason, certain of the spaces normally occupied by the mileage figures are left blank. Assuming that the strap 35 is positioned in the manner shown in Figure 6, wherein the top line of the strap registers with the space on the folder containing "Detroit, Michigan", it will be noted that the mileage space registering with the indicia "Detroit, Michigan" on the strap is, of course, left blank. This procedure is followed wherever there is a duplication of cities or towns on the strap and in the column 31.

60 It will also be apparent from Figure 6 that the exposed surfaces of the flaps are provided with indicia. The flap 30 is provided with a column 36 arranged as a continuation of the column 31 75

and divided by transverse lines 37 into a plurality of spaces 38. Arranged in each space 38 is a city or town and registering with each space 38 is a transverse column 39 divided into a plurality of spaces 40. The flap 30' is also provided with columns 41 forming, in effect, continuations of the columns 39 and also divided into spaces 40. The number of spaces on the flap 30 correspond to the number of locations on the adjacent side of the strap 35 and the number of spaces on the flap 30' correspond to the number of locations on the opposite side of the strap. Arranged in each space 40 is indicia representing either actual mileage, or some other information data in regard to the particular geographic locations listed. In the interests of simplicity, I have shown actual mileage figures in the spaces 40 so that the flaps may be considered as merely forming a continuation of the side wall portions 20 of the folder.

In operation, assuming that it is desired to find the distance between "Detroit, Michigan" and "Washington, D. C.", the strap 35 is adjusted to register the top edge thereof with the city 25 "Detroit, Michigan" in the column 31 on the side 29. Inasmuch as "Washington, D. C." appears on the opposite side of the strap, it is necessary to reverse the folder and read the mileage 531 in the column 41 on the side 29' opposite the 30 geographical location "Washington, D. C." on the strap. In the event it is desired to determine the mileage, for example, between "Detroit, Michigan" and "Louisville, Kentucky", the strap is registered with the indicia "Detroit, Michigan" 35 in the column 31 on the wall 29 of the folder. In view of the fact that the indicia "Louisville, Kentucky" is on the same side of the strap, it is not necessary to reverse the folder and the mileage 389 may be read directly opposite the indicia "Louisville" on the strap.

However, the figures in the spaces 40 may be readily changed to indicate different informative data in regard to the particular geographical locations listed. For example, these figures may indicate the telephone toll charges between any 45 one of the cities in the column 36 and the cities on the strap 35, or it is possible to insert indicia

in the spaces 40 imparting the difference in the time between the geographic points listed in the column 36 and on the strap 35. Also, the opposed sides of the folder and the flaps may be employed to indicate different information in regard to the selected geographic locations. In other words, one side of the device may be used to afford information in regard to telephone toll charges and the other side employed to give the actual mileage. It follows from the above that 10 various changes may be made in either of the two constructions selected herein for the purpose of illustration without departing from the spirit and scope of this invention.

It will be noted from Figure 8 that the strap 35 15 not only acts as a finder for the calculating device, but serves to hold the flaps 30 and 30' adjacent the side wall portions 29 and 29' when the device is not in use. In this position of the strap, the device may be employed as a folder 20 to retain a map or other loose data.

What I claim as my invention is:

A computing device comprising a relatively long strip having on one face thereof a column of indicia representing different geographical locations, said strip being folded along a transverse line substantially midway of the geographical indicia to provide a folder having indicia both on the front and back thereof, and a folded relatively narrow one-piece strap embracing both 30 folds of the strip and having its ends secured together, said folded strap being slidable longitudinally on said folder and snugly engaging the longitudinal edges of the folder to hold the folds together, said strap having a column of indicia 35 arranged transversely with respect to said first-mentioned column and representing geographical locations, said folder also having numerical data arranged in alignment with both the first and second mentioned columns and adapted when 40 one edge of the strap registers with a geographical location in the first-mentioned column to indicate a numerical relation between the location in registry with the strap edge and the locations designated in the column on the strap. 45

WILLIAM G. STEWART.
